GREASE FILLING MACHINE

Application filed March 20, 1929. Serial No. 348,580.

This invention relates to improvements in filling machines and its purpose is to provide an improved apparatus whereby greases and other relatively heavy liquids, and the like, may be filled into cans or other receptacles. Greases and other heavy liquids are commonly distributed to the retail trade in relatively small cans each containing a predetermined measured quantity of grease and the principal object of the present invention is to provide an improved apparatus whereby such liquids may be efficiently and quickly filled into cans in predetermined quantities. Another object of the invention is to provide an improved filling apparatus particularly adapted for filling heavy liquids, such as greases, into cans without leaving any unoccupied voids or spaces within the can. A further object of the invention is to provide a machine having a plurality of measuring chambers in combination with a rotating filling head having a plurality of discharge nozzles with means for automatically controlling the discharge of the grease or other liquid from each nozzle during the rotation of the head. Still another object of the invention is to provide an improved grease filling machine comprising a rotating table on which the cans are supported in combination with a series of rotating nozzles each comprising an adjustable extension adapted to be automatically withdrawn from the can during the filling thereof or after the filling operation has been completed. Other objects relate to various features of construction and arrangement which will appear more fully hereinafter.

The nature of the invention will be understood from the following specification taken with the accompanying drawings. In the drawings,

Fig. 1 shows a side elevation of a filling machine embodying the improvements of the present invention;

Fig. 2 shows a top plan view of the machine illustrated in Fig. 1;

Fig. 3 shows a vertical section taken on the line 3—3 of Fig. 2;

Fig. 4 is a detail horizontal section taken on the line 4—4 of Fig. 3;

Fig. 5 is a horizontal section taken on the line 5—5 of Fig. 3;

Fig. 6 is a horizontal section taken on the line 6—6 of Fig. 3, showing the valve mechanism for controlling the flow of fluid to and from each measuring cylinder;

Fig. 7 is an enlarged horizontal section similar to that of a portion of Fig. 6, showing the valve mechanism for one cylinder with the parts thereof in position to permit the flow of grease or the like into one end of the connected measuring chamber;

Fig. 8 is a horizontal section similar to that of Fig. 7, showing the relative positions of the parts of the valve mechanism after the valves have been reversed from the arrangement shown in Fig. 7;

Fig. 9 shows an enlarged vertical section on the line 9—9 of Fig. 2, showing the automatically operated nozzle mechanism by which the grease or other liquid is filled into the cans.

Fig. 10 is a horizontal section taken on the line 10—10 of Fig. 9;

Fig. 11 is a horizontal section taken on the line 11—11 of Fig. 9;

Fig. 12 is an enlarged horizontal section taken on the line 12—12 of Fig. 9, showing the cam by which the movable sections of the nozzle are elevated;

Fig. 13 is a vertical section through a can during the process of filling, showing the flow of grease or the like from the nozzle extension when in its lower position;

Fig. 14 is a vertical section similar to that of Fig. 13, showing the condition after the can is substantially filled with grease, and

Fig. 15 is a section similar to that of Figs. 13 and 14, showing the condition after the

can has been entirely filled and the nozzle extension has been withdrawn from the can.

As illustrated in the accompanying drawings, the improved filling machine comprises a supporting base 20, having an upwardly extending circular part 20^a which is hollowed out as shown at 21 to form a housing for a worm wheel 22 which is secured on a vertical operating shaft 23. This shaft is journaled 10 in a bearing 24 formed in the base beneath the chamber 21 and extends upwardly through the housing cover 25 in which it is journaled. The cover 25 is secured to the portion 20^a of the base by means of studs 15 26 and the central hub portion 25^a of the cover is threadedly engaged by a hollow sleeve or standard 27 through which the operating shaft 23 passes. The upper end of the shaft 23 is tapered as shown at 23^a to fit the correspondingly tapered bore of a hub member 28 secured to the circular top plate 29 of a rotatable head 30. The head 30 is secured 20 against rotation with respect to the shaft 23 by a key engaging the tapered portion 23^a and the hub 28. The extreme upper end of the shaft 23 is threaded for engagement by a nut 31 which holds the head 30 against vertical displacement. The head 30 comprises 25 a plurality of measuring cylinders 33 which register with apertures 34 formed in the top plate 29 and extend downwardly therefrom, being closed at their upper ends by relatively thin cover plates 35 which engage annular recesses around the openings 34 and which 30 are maintained in place by cross bars 36 secured to the plate 29 by studs 37. The lower end of each measuring cylinder 33 is closed by a plate 38 and the entire group of cylinders 33, of which four are illustrated in the present embodiment, is surrounded by a depending sheet metal skirt 39 which is attached to an annular flange 29^a formed on the under side of the outer portion of the top plate 29. The skirt 39 is cylindrical in form and extends 40 downwardly to the lower edges of the cylinders 33, being beaded at its lower edge as shown at 39^a.

The head 30 with its measuring cylinders 33 is adapted to carry the cans to be filled and 45 to rotate on the standard 27, during which time the grease or other liquid to be filled into the cans is forced into the cylinders 33 and discharged from these cylinders successively into the cans. The rotation of the head 30 is effected through driving connections to the operating shaft 23 upon which the worm wheel 22 is mounted. The worm wheel 22 meshes with a worm 40 which is 50 fixed on a horizontal shaft 41 journaled in bearings 42 secured to the lateral extension 20^b of the base. This shaft 41 has a stepped pulley 43 fixed thereon and is driven by a belt 44 which connects this stepped pulley with another stepped pulley 45 secured on a 55 horizontal driving shaft 46. The shaft 46 is

journaled in a bearing 46^a secured to the extension 20^b of the base and it is also journaled in bearings carried by the housing of a pump 47 by which the grease or other liquid is pumped to the measuring cylinders 33. The shaft 46 has a sprocket gear 48 fixed thereon and this gear is driven by a sprocket chain 49 connected to another sprocket gear 50 fixed on the shaft 51 of a driving motor 52. The driving motor 52 and the pump 47 are both mounted on the base 20^b and the motor is connected in an electric circuit by suitable connections, not shown, which may, if desired, be arranged to permit adjustment of the speed of the motor. 70 75 80

The pump 47 is of the centrifugal type and the grease or other liquid to be filled into the cans is drawn into the pump chamber through an inlet conduit 53, being subsequently discharged from the pump case through a discharge pipe 54 which extends upwardly, as shown in Fig. 1, and thence horizontally as shown at 54^a. The horizontal portion of the discharge pipe has a valve 55 connected therein which is operated by a handle 55^a to permit the flow of grease to be shut off when desired. A pressure gauge 56 is connected in the pipe 54 to indicate the pressure of the grease being forced from the pump to the measuring cylinder 33. The horizontal portion 54^a of the discharge pipe is connected through an elbow 57 with a short vertical extension 54^b which is threadedly engaged at its lower end by the coupling sleeve 58. This sleeve is engaged on its lower end by another sleeve 59 having a collar 60 threaded thereon and provided with an overhanging annular flange 60^a which engages the upper side of the outwardly directed annular flange 58^a formed 90 95 100 on the coupling sleeve 58. The sleeve 59 threadedly engages a tubular threaded member 61 which in turn has a threaded engagement with an aperture 62 formed in the upper side of a four-way coupling 63. The chamber 63^a of the coupling member 63 has communication with four branch openings 63^b each of which is threadedly engaged by a relatively short horizontal outlet pipe 64. 110 115 120 These outlet pipes are connected through elbows 65 with downward extensions 64^a which are mounted adjacent the cylinders 33 to rotate with the head 30. During the rotation of the head, the discharge pipe 54 and the connected coupling sleeve 58 remain stationary while the lower coupling sleeve 59 and its collar 60 revolve with the flange 60^a sliding over the flange 58^a and forming a fluid-tight joint. 125

Each branch supply pipe 64 extends vertically downward through an aperture 66 in the top plate 29 of the head in a position adjacent to and radially inward from one of the cylinders 33, so that one branch supply pipe 64 is adapted to supply grease or the 130

like to its adjacent measuring cylinder. The flow of grease from each supply pipe 64 to its adjacent cylinder 33 takes place through certain valve mechanism indicated generally at 67 and illustrated more particularly in Figs. 7 and 8. The lower end of each vertical portion 64^a of each branch supply pipe is connected to an elbow 68 with a horizontal extension 64^b which communicates with a three-way connector 69. Each connector has a pair of horizontally directed pipes 70 and 71 leading therefrom and communicating with the casings of the valves 72 and 73, respectively. Each valve casing has an internal cylindrical chamber and these chambers contain the rotatable valve members 72^a and 73^a. The valve member 72 has a passage 74 extending therethrough and communicating with a rightangularly disposed branch passage 74^a. The valve member 73^a is similarly provided with a passage 75 extending therethrough and communicating with a branch passage 75^a. The valve casing 72 has one port 76^a communicating with a pipe 70 and two other ports 76^b and 76^c each communicating, respectively, with the adjacent cylinder and with a nozzle through which the grease is filled into the can. When the valve member 72 is in the position shown in Fig. 7, a communication is established from the pipe 70 through the port 76^a, valve passages 74 and 74^a and port 76^b, with a pipe 77 which communicates through suitable elbows and other connections with the bottom of the adjacent cylinder 33 through its lower wall 38. When the valve member 72 is turned through ninety degrees to occupy the position shown in Fig. 8, a communication is established through the valve casing from the pipe 77 through the ports 76^b and 76^c to a vertical discharge pipe 78 which extends upwardly adjacent the cylinder and communicates with one of the discharge nozzles 80. The valve casing 73 is similarly provided with a port 81^a communicating with the pipe 71 and two other aligning ports 81^b and 81^c. When the valve member 73^a is in the position shown in Fig. 8, a communication is established from the pipe 71 through the port 81^a, valve passages 75 and 75^a and port 81^b with a pipe 82 which communicates with the chamber of the adjacent cylinder 33 through the side wall thereof substantially midway between its upper and lower ends, as shown in Fig. 1. When the valve member 73^a is turned to the position shown in Fig. 7, a communication is established from the side of the cylinder 33 through the pipe 82, port 81^b, valve passage 75 and port 81^c with a discharge or outlet pipe 79 which extends upwardly adjacent the cylinder and terminates in another discharge nozzle 80 located above the top plate 29 of the head 30.

Each measuring cylinder 33 is thus provided with two outlet pipes 78 and 79 and with

two connected discharge nozzles 80 and the grease which is filled into the cylinder 30 through the supply pipe 64 is adapted to be discharged alternately through the two outlet pipes 78 and 79. To effect this alternate discharge of predetermined quantities of grease from different parts of each measuring cylinder, the force of the incoming grease is made use of to expel the measured quantity of grease previously drawn into the cylinder. Each cylinder 33 is therefore provided with a cylindrical piston 85 which divides the space within the cylinder into a lower measuring chamber 86 and an upper measuring chamber 87. The grease forced into the cylinder through the pipe 77 passes into the chamber 86 and thereby forces the piston 85 upwardly, thereby expelling any grease in the chamber 87 through the communicating discharge pipe 82 which communicates with the space 87 through the side wall of the cylinder. In a subsequent operation, the grease is forced under pressure into the space 87 thereby causing the piston 85 to move downwardly and force the grease outwardly from the space 86 through the pipe 77 and the connected discharge pipe 78. In order to vary the quantity of grease drawn into the cylinder 30 on one stroke of the piston 85, the upper portion of each cylinder is partially occupied by a cylindrical filler block 88 which is carried by an adjusting screw 89 having a threaded engagement with a hub 36^a of the bar 36 which extends across the top end of the cylinder above the cover plate 35. When the filler block 88 is adjusted downwardly by turning the screw 89, having the hand wheel 89^a at the upper end thereof, the path of travel of the piston 85 is thereby limited so that the volume of grease drawn into either chamber 86 or 87 upon one stroke of the piston is reduced. By suitably adjusting the position of the filler block 88, the quantity of grease drawn into the cylinder on one stroke of the piston 85, and subsequently ejected therefrom on a reverse stroke of the piston, may be regulated to suit the capacity of the cans being filled. The filler block 88 is provided with a groove 90 extending across its lower face and up two opposite sides thereof so that when the filler block 88 is in a lower position where it is opposite the port leading to the pipe 82, the flow of grease to and from the pipe 82 may take place around the block 88 through the groove 90. Each block 88 is provided with a rod 91 having a sliding engagement with the top wall of the cylinder and with the cross bar 36 so that the block 88 is prevented from turning when being adjusted by the screw 89. Each piston 85 is preferably provided with suitable packing rings of leather or the like to prevent the escape of grease or other liquid from one measuring chamber 86 or 87 to the other. The valve members 72^a and 73^a are auto-

matically operated during the rotation of the head 30 to cause grease to be drawn into and discharged from the various measuring cylinders 30 at the proper intervals during the 5 rotation of the head. Each valve member 72^a has a shaft extending through the wall of its casing 72 and connected to an intermediate part of an operating lever 92. Each valve member 73^a is similarly provided with a projecting shaft which extends through the wall 10 of its casing 73 and is connected to the intermediate part of an operating lever 93. The opposite ends of these levers 92 and 93 are pivotally connected to the ends of a pair of 15 connecting links 94. These links are also pivotally connected to a trip lever 95 having a body portion 95^a which extends parallel to the levers 92 and 93, being pivotally connected to the links 94 at the points 96. Each trip 20 lever 95 has an operating arm 95^b extending toward the outer side of the head 30 and directed at an angle of about forty-five degrees to the body portion 95^a. Each trip lever 95 is also provided with a tangentially extending 25 operating arm 95^c which is directed at an angle of forty-five degrees to the body portion 95^a and at an angle of ninety degrees to the operating arm 95^b. These operating arms 95^b and 95^c are adapted to be engaged by stationary mounted rollers during the rotation 30 of the head 30 for the purpose of shifting the links 94 and thereby operating the valve levers 92 and 93. As shown in Fig. 6, the arm 95^b is adapted to be engaged by an outer roller 35 98 while the inwardly projecting arm 95^c is adapted to be engaged by an inner roller 99. The roller 98 is rotatably mounted at the upper end of a post 100 which extends upwardly from the base 20, as shown in Fig. 1, 40 and the roller 99 is rotatably mounted on a pin 101 which extends upwardly from the housing cover 25.

The operation of the valve mechanism 67 may thus be understood by reference to Figs. 45 5, 6, 7 and 8. In Fig. 7 there is illustrated the relative positions of the parts of the valve mechanism 67 when the outer arm 95^b of the trip lever is in engagement with the outer roller 98, corresponding to the lower 50 set of valve mechanism 67 illustrated in Fig. 6. After the head 30 has rotated through one hundred and eighty degrees, the inner arm 95^c of the trip lever is brought into engagement with the inner stationary roller 99, as 55 shown in the upper part of Fig. 6, and that arrangement of the parts, on an enlarged scale, is illustrated in Fig. 8. Although two different sets of valve mechanism are shown in these different positions in Fig. 6, it will 60 be understood that each of the four valve mechanisms passes successively through each of these stages. When the inner arm 95^c of the trip lever of a particular valve mechanism is in engagement with the outer roller 65 98, as shown in Fig. 7, the valve member 72^a

is turned so that a communication is established from the supply pipe 64 and branch pipe 70 through the valve casing 72 to the pipe 77 which communicates with the bottom chamber 86 of the adjacent measuring cylinder 33. The grease is then forced into this chamber 86 under pressure by the action of the pump 47 until the piston 85 is forced to the upper limit of its travel as determined by the position of the filler block 88. As this operation of filling the space 86 goes on, the head 30 continues to rotate and, during this rotation, the upward movement of the piston 85 forces the grease which has previously been drawn into the space 87 outwardly 80 through the pipe 82 and thence through the valve member 73^a, occupying the position shown in Fig. 7, to the outlet pipe 79 through which the grease passes to a discharge nozzle 80 and is delivered by that nozzle to one of the cans 105 positioned on the top plate 29. This filling of the can 105 continues during the rotation of the head 30 until the piston 85 of that measuring cylinder reaches the upper limit of its travel. The period of time 90 during which this filling operation takes place will depend upon the speed of operation of the pump and the capacity of the cans being filled but it will have been completed before the cylinder and its valve mechanism 95 reaches the reversed position shown in Fig. 8 at the end of one hundred and eighty degrees of travel. When that reversed position is reached, the inner arm 95^c of the trip lever 95 is engaged by the inner roller 99 100 thereby moving the valve mechanism to the position shown in Fig. 8. A communication is then established from the supply pipe 64 through the pipe 71 and through the valve member 73^a to the pipe 82 leading to the space 105 87 above the piston 85 in the associated measuring cylinder 22. The grease then flows into the space 87 under the pressure exerted by the pump 47 and at the same time the grease previously forced into the space 86 beneath the piston is discharged therefrom through the pipe 77 and thence through the valve member 72^a, occupying the position shown in Fig. 8, and finally through the pipe 78 to one of the discharge nozzles 80 where it is 110 delivered to another of the cans 105. This filling of the can from the outflow through the pipe 78 continues as the cylinder and its valve mechanism pass around in the direction of the arrow 206 from the uppermost position shown in Fig. 6 toward the lowermost position shown in that figure. Thus, during one complete revolution of the head 30, two cans are filled from each measuring cylinder 33 and the grease which is pumped into one measuring space of the cylinder serves to supply the force by which the quantity of grease previously drawn into the other measuring space of that cylinder is 120 discharged into a can. 130

The filling of heavy grease and the like into cans has heretofore presented difficulties due to the fact that if the grease be discharged from the nozzle at a point adjacent to the top of the can, the grease may pile up in irregular fashion in the can and leave air spaces or voids so that the can does not become entirely filled with grease. One of the important features of the present invention is the provision of improved means for causing the grease to be discharged into each can from the mouth of a nozzle positioned adjacent the bottom of the can, the nozzle being subsequently withdrawn from the can to permit the removal of the filled can from the machine. For this purpose, each nozzle 80 which is directed downwardly in a vertical position, is provided with a tubular nozzle extension 106 which slidably engages the counter-bore 107 of the main nozzle 80 and which may be moved downwardly into a can 105 when the can is positioned on the top plate 29 of the rotatable head 30. The upper end of each nozzle extension 106 is pivotally connected to the lower end of a rod 108 which is slidably mounted in a vertical sleeve 109 formed integrally with or secured to the nozzle 80 and extending upwardly therefrom, as shown in Fig. 10. The rod 108 extends above the sleeve 109 and is engaged by a collar 110 secured in adjusted position thereon by means of a set screw 111. This collar 110 may be adjusted on the rod 108 to limit the extent of downward movement of the nozzle extension 106 within the nozzle 80. Means are provided for elevating the rods 108 and their connected nozzle extensions 106 and the cans are placed beneath the nozzles on the plate 29 while the members 106 are elevated. As the head 30 continues to rotate, the rods 109 are released so that the nozzle extensions 106 are successively permitted to drop by gravity into the respective cans positioned beneath them.

The mechanism for elevating the nozzle extensions 106 at the proper location during the rotation of the head 30 is shown particularly in Figs. 9 to 15, inclusive, and it comprises a circular guide plate 115 mounted on standards 116 which are secured to the horizontal portions of the pipes 64 and having a central aperture 115^a which is engaged by the coupling sleeve 58 previously described. The guide plate 115 has a downwardly and outwardly inclined upper annular surface 115^a and this surface has formed therein a plurality of downwardly inclined guides 117 located in radial planes each of which includes the axis of one of the rods 108. Slidably mounted in each guide 117 is a bar 118 and each of these bars 118 is pivoted at 119 to a connecting rod 120 having its lower end secured to a clevis 121, shown in Fig. 10, the arms of which extend on opposite sides of one of the sleeves 109. The arms of the

clevis are engaged by a fixed pin 122 which passes through slots 123, formed in the opposite side walls of the sleeve 109, and closely fits an aperture in the rod 108. Rollers 124 are mounted on the pin 122 between the rod 108 and the arms of the clevis 121 so that these rollers travel in the slots 123 when the rod 108 and its connected nozzle extension 106 move vertically. The downward movement of these valve extensions takes place by gravity, as previously explained, but the upward movement is effected by means of a cam 125 engaging pins 126 which extend upwardly from the bars 118 carried by the guide plate 115. The cam 125 has a hub 127 which is secured to the stationary portion 54^a of the supply pipe by means of set screws 129. The body portion of the cam extends outwardly and downwardly parallel to the surface 115^a of the guide plate and is provided with a flange 125^a directed downwardly at right angles to the surface 115^a. The inner surface 125^b of this flange 125^a coacts with the pins 126 and the distance of this surface 125^b from the axis of rotation of the head 30 decreases in the direction of rotation of the head which is indicated in Fig. 12 by the arrow 130. As the bars 118 and their upwardly extending pins 126 are carried around by the rotating guide plate 115, the pins 126 are brought successively into engagement with the downwardly extending inclined surface 125^b of the stationary cam. This moves the bars 118 inwardly and operates through the connecting rods 120 to effect an upward movement of the nozzle extensions 106, which are thereby withdrawn from the cans 105. This withdrawal of the nozzle extension from the cans should preferably take place, in the embodiment illustrated, in the position indicated at 131 in Fig. 2, and the surface 125^b is provided at its inner portion with a part 125^c which is substantially concentric with the axis of rotation of the head so that there is a period during which each nozzle extension 106 is held in its extreme elevated position to permit the operator to remove a filled can and replace it by an empty can. The cam 125 may be adjusted in its angular position on the pipe 54^a to cause this elevation of the nozzle extensions to take place at any desired point in the rotation of the head and the extent of upward movement of the nozzle extension may be regulated by adjusting the lengths of the connecting rods 120, each of which is provided with a central internally threaded sleeve 120^a which is engaged by the externally threaded end portions 120^b.

Due to the use of the nozzle extensions 106, the filling of the cans 105 may be caused to take place substantially as illustrated in Figs. 13, 14 and 15. In Fig. 13 the nozzle extension 106 is shown extending below the lower end of the main nozzle 80 to a position wherein its

mouth is located adjacent the bottom of the can 105 and the grease 133 being discharged from the nozzle is filling the can from the bottom upwardly, the surface thereof being indicated generally at 133^a. As the filling continues, the upper surface of the grease rises upwardly around the nozzle extension 106 as shown at 133^b in Fig. 13. The filling continues until a point is reached when the can is nearly filled where the surface of the grease approaches the top of the can as shown at 133^c in Fig. 14, while the mouth of the nozzle remains near the bottom of the can. In Fig. 15, the can 105 is shown entirely filled with grease and the nozzle extension 106 has been withdrawn therefrom by the action of the cam 125.

Although one form of the invention has been shown and described by way of illustration, it will be understood that it may be constructed in various other embodiments within the scope of the appended claims.

We claim:

1. The combination in a filling machine, of a rotatable head having a plurality of nozzles, means for supporting a plurality of cans in register with said nozzles, a nozzle extension carried by each of said nozzles and movable with respect to the remainder of that nozzle into one of said cans, means for measuring predetermined volumes of liquid, means for successively discharging previously measured volumes of liquid under pressure from said nozzle extensions while located in said cans, and means actuated during the rotation of said head for withdrawing said nozzle extensions successively from said cans as they are filled.

2. The combination in a filling machine, of a movable support for a plurality of cans to be filled, a plurality of nozzles movable with said support, said nozzles having relatively movable extensions each movable longitudinally into the lower part of one of said cans on said support, means for limiting the movement of said extensions into said cans, and means for withdrawing said extensions from said cans.

3. The combination in a filling machine, of a movable support for a plurality of cans to be filled, a plurality of nozzles movable with said support, said nozzles having slidably mounted extensions each movable into one of said cans on said support, means for limiting the movement of said extensions into said cans, means movable with said nozzles for successively discharging measured quantities of liquid from said nozzle extensions into said cans, and means actuated during the movement of said support for automatically and successively withdrawing said nozzle extensions from said cans.

4. The combination in a filling machine, of a movable support for a plurality of cans to be filled, a plurality of nozzles movable

with said support, said nozzles having extensions each movable into one of said cans on said support, means for limiting the movement of said extensions into said cans, means for discharging a quantity of liquid under pressure from each of said nozzle extensions into a can, means for withdrawing said nozzle extensions from said cans after they are filled, and means for adjusting the extent of movement of said nozzle extensions.

5. The combination in a filling machine, of a rotatable head, a support for a plurality of cans carried by said head, a plurality of measuring chambers carried by said head, a plurality of discharge nozzles each having communication with one of said measuring chambers, means for moving a part of each of said nozzles with respect to the remainder of that nozzle into a can, a movable piston for discharging a measured quantity of liquid from each of said measuring chambers through one of said nozzles into a can, and means actuated during the rotation of said head for successively withdrawing said parts of said nozzles from said cans as they are filled.

6. The combination in a filling machine, of a rotatable head, a plurality of measuring cylinders carried by said head, each of said cylinders comprising a plurality of measuring chambers, means for forcing a liquid into each of the measuring chambers of said measuring cylinders in predetermined sequence, a plurality of discharge pipes each having communication with one of said measuring chambers, means actuated by the movement of said liquid into one measuring chamber for automatically discharging a predetermined quantity of liquid from another chamber of the same cylinder, a plurality of movable nozzles each connected with one of said discharge pipes, a can support carried by said head for supporting a plurality of cans each positioned to receive one of said nozzles, and means actuated during the rotation of said head for automatically withdrawing said nozzles from said cans as they are filled.

7. The combination in a filling machine of a movable support for a plurality of cans, a plurality of nozzles movable with said support, each of said nozzles having a telescoping downward extension adapted to be moved downwardly into one of said cans with its mouth adjacent the bottom of said can, means for discharging a measured volume of liquid through each of said nozzles into its can, and means actuated during the movement of said support for automatically withdrawing each of said nozzle extensions from each can at a predetermined point in the travel of said support.

8. The combination in a filling machine, of a movable support for a plurality of cans, a plurality of nozzles with each of which one of said cans is adapted to register, a plural-

- ity of cylinders movable with said support and each having a connection from opposite end portions thereof with two of said nozzles, a piston mounted in each of said cylinders, and means for admitting fluid under pressure to either end of each cylinder and thereby actuating the piston in said cylinder to discharge fluid under pressure through one of said nozzles from the other end of 10 that cylinder.
9. The combination in a filling machine, of a support for a plurality of cans, a plurality of nozzles with each of which one of said cans is adapted to register, a plurality 15 of cylinders each having a connection from opposite end portions thereof with two of said nozzles, a piston mounted in each of said cylinders, means for admitting fluid under pressure to either end of each cylinder and thereby actuating the piston in said cylinder to discharge fluid under pressure through one of said nozzles from the other end of that cylinder, each of said nozzles having a relatively movable extension adapted to project 20 through the mouth of one of said cans, and means for moving said nozzle extensions.
10. The combination in a filling machine, of a rotatable head, a plurality of measuring cylinders mounted on said head, each of said 25 cylinders comprising a pair of measuring chambers, a piston mounted in each of said cylinders between the measuring chambers thereof, a plurality of nozzles, each of said cylinders having one of said nozzles connected with each of its measuring chambers, means for admitting liquid under pressure to each of said measuring chambers during the rotation of said head, and valve means controlling the communication of each of 30 said measuring chambers with said last named means and with said nozzles whereby the admission of liquid under pressure to one measuring chamber discharges liquid under pressure from the other measuring chamber 35 of that cylinder through one of said nozzles.
11. The combination in a filling machine, of a rotatable head, a plurality of measuring cylinders mounted on said head, each of said cylinders comprising a pair of measuring 40 chambers, a piston mounted in each of said cylinders between the measuring chambers thereof, a plurality of nozzles, each of said cylinders having one of said nozzles connected with each of its measuring chambers, 45 means for admitting liquid under pressure to each of said measuring chambers during the rotation of said head, valve means controlling the communication of each of said measuring chambers with said last-named means and with said nozzles whereby the admission of liquid under pressure to one measuring chamber discharges liquid under pressure from the other measuring chamber of that cylinder through one of said nozzles, a support 50 for cans movable with said cylinders, and a telescoping extension for each of said nozzles movable into one of said cans.
12. The combination in a filling machine, of a rotatable head adapted to support a plurality of cans, a plurality of nozzles carried by said head with each of which one of said cans is adapted to register, a slidable extension through each of said nozzles movable downwardly into a can, an upwardly extending rod attached to each of said nozzle extensions, a series of connections extending inwardly from said rods toward the axis of rotation of said head, a stationary cam, and means attached to said connections for engaging said cam and automatically withdrawing said nozzle extensions from said cans during the rotation of said head. 55
13. The combination in a filling machine, of a rotatable head adapted to support a plurality of cans, a plurality of nozzles carried by said head with each of which one of said cans is adapted to register, a slidable extension through each of said nozzles movable downwardly into a can, an upwardly extending rod attached to each of said nozzle extensions, a series of connections extending inwardly from said rods toward the axis of rotation of said head, a stationary cam, means attached to said connections for engaging said cam and automatically withdrawing said nozzle extensions from said cans during the rotation of said head, and adjustable means for limiting the downward movement of said nozzle extensions to vary their projection 60 into said cans.
14. The combination in a filling machine, of a rotatable head, a support for carrying a plurality of cans on the same level, a plurality of measuring chambers carried by said head, a plurality of discharge nozzles each having communication with one of said measuring chambers and each having a separate part movable toward said support, means for moving said parts of said nozzle, successively into a series of cans carried by said support, a movable piston for discharging a measured quantity of liquid under pressure from each of said measuring chambers through one of said nozzle parts into a can, and means actuated during the rotation of said head for successively withdrawing said parts of said nozzles from said cans as they are successively filled. 65
- In witness whereof, we have subscribed our names.
